UNITED STATES PATENT OFFICE.

JOHN T. CALLAHAN, OF MILFORD, MASSACHUSETTS, ASSIGNOR TO ARCHER RUBBER COMPANY, OF MILFORD, MASSACHUSETTS, A CORPORATION OF MASSACHUSETTS.

SLIPPER AND METHOD OF MAKING SAME.

Application filed April 11, 1928. Serial No. 269,051.

This invention relates to slippers, and more particularly to those made of flexible sheeting and especially adapted for travel, household, or beach use.

5 The slipper of the present invention may be made of flexible sheeting of the character comprising a textile fabric surfaced with rubber, the fabric being on the inside and the rubber on the outside of the slipper. 10 An upper and an outer sole are attached by stitching, apertures preferably being formed through the toe portion, near the sole, to permit ventilation of the foot. An inner sole of similar sheeting is provided, 15 with its rubber side attached to the fabric side of the outer sole as by rubber cement.

With these and other features in view, the invention consists in the construction and arrangement of parts hereinafter described 20 in conjunction with the accompanying drawings, wherein—

Figure 1 represents a plan view of a slipper made in accordance with the present invention.

25 Figure 2 is a side view of the same.

Figure 3 is a fragmentary section on the line 3—3 of Figure 1.

Figure 4 is a transverse section through the slipper on the line 4—4 of Figure 2, being partly broken away.

30 Figure 5 is a sectional detail illustrating the method of attaching the upper and outer sole.

Referring to the drawings, 1 represents 35 the upper of the slipper, the rubber side *r* being on the outside and the fabric side *t* being on the inside of the slipper. The upper is shown as one piece, which is stitched together at its back at 2, its upper marginal portion being folded over on the outside at 3 and stitched in place as shown best in 40 Figure 4. The upper is stitched to an outer sole 4, as shown in Figures 3 and 4, no last being required. The stitching is done with the upper and sole wrong side out, as illustrated in Figure 5, the stitched parts then 45 being turned right side out, the raw edges *e* beyond the line of stitching being turned inwardly, as shown in dotted outline. The overlying, inwardly turned edges *e* are 50 preferably cemented together and cemented down to the sole. An inner sole 5 is then provided with its rubber side contacting with the fabric side of the outer sole, the

sole 5 preferably being of sufficient width to 55 cover the raw edge portions of the upper and outer sole beyond the line of stitching and preferably being cemented down in place by rubber cement. Inasmuch as fabric of the character described is insufficiently 60 porous to permit adequate ventilation of the foot, provision is made to obviate this difficulty. To this end, a plurality of apertures 6 are shown as formed through the toe portion of the upper, near the sole, these 65 apertures permitting access of air to the foot and also serving as outlets for water which may enter the slipper during bathing. The inner sole 5 is also preferably provided with apertures 8 arranged in transverse 70 zones, the inner sole at these zones preferably being uncemented to the outer sole so that air entering the slipper through the aperture 6 may circulate under the inner sole through the apertures 8 to the sole of 75 the foot.

A slipper such as described is of comparatively simple and inexpensive construction, and may be manufactured from the comparatively large clippings that result from 80 raincoat manufacture or from the "seconds" or short ends produced in the manufacture of sheeting. The fabric interior is comfortable to the foot, and the rubber exterior may be easily washed. Because it may be 85 readily folded into a compact package, it is especially suitable for use by the traveling man. The high flexibility of the sheeting also permits the slipper to be turned inside out, so that when the fabric becomes 90 wet it may be readily dried. Of course, the slipper may be made of other material, if desired, and may be used for other purposes, e. g., as a house slipper.

Having thus described an embodiment of 95 this invention, it is evident that various changes might be made therein without departing from the spirit or scope of invention as set forth in the appended claims.

What I claim is:

1. A slipper of the character described, 100 made entirely of flexible sheeting, comprising a fabric inside and a rubber outside, said slipper comprising an upper stitched to an outer sole and an inner sole with its rubber 105 side cemented to the fabric side of the outer sole, said slipper having ventilation apertures through its toe portion near the sole.

2. A slipper of the character described, made entirely of flexible sheeting, comprising a fabric inside and a rubber outside, said slipper comprising an upper stitched to an outer sole with the raw edge portions beyond the line of stitching on the inside, and an inner sole with its rubber side cemented to the fabric side of the outer sole and covering said raw edge portion, said slipper having ventilation apertures through its toe portion near the sole and the inner sole being provided with apertures arranged in transverse zones, the inner sole at such zones being uncemented to the fabric of the outer sole.
3. A method of making slippers of flexible

sheeting comprising a fabric inside and a rubber outside, which comprises stitching together the marginal portions of an upper and an outer sole with the fabric on the outside, turning the stitched parts right side out so that the raw edge portions beyond the line of stitching are turned inwardly, cementing down the raw edge portions to the sole, and then cementing to said outer sole the rubber side of an inner sole of similar material covering the inwardly turned edge portions.

In testimony whereof I have affixed my signature.

JOHN T. CALLAHAN.
